US0D1074158S

(12) **United States Design Patent** (10) **Patent No.:** **US D1,074,158 S**
(45) **Date of Patent:** **** May 13, 2025**

(54) **NAIL**

(71) Applicant: **BESTGRIP S.R.L.**, Gandino (IT)

CN 304313622 * 10/2017
CN 304518858 * 2/2018

(72) Inventor: **Luca Maffeis**, Gandino (IT)

(Continued)

(73) Assignee: **BESTGRIP S.R.L.**, Gandino (IT)

(**) Term: **15 Years**

(21) Appl. No.: **35/519,279**

(22) Filed: **Oct. 27, 2023**

(80) **Hague Agreement Data**

Int. Filing Date: **Oct. 27, 2023**

Int. Reg. No.: **DM/233441**

Int. Reg. Date: **Oct. 27, 2023**

Int. Reg. Pub. Date: **Dec. 8, 2023**

(30) **Foreign Application Priority Data**

May 9, 2023 (EM) 015020903-0001
May 9, 2023 (EM) 015020903-0003

(Continued)

(51) **LOC (15) Cl.** **02-04**

(52) **U.S. Cl.**

USPC **D2/962; D12/608**

(58) **Field of Classification Search**

USPC D12/604, 608; D8/386, 387, 391;
D2/962

(57) **CLAIM**

The ornamental design for a nail as shown and described.

DESCRIPTION

Nail

1.1 : Top Perspective

1.2 : Bottom Perspective

1.3 : Front and rear view

1.4 : Right and left view

1.5 : Top

1.6 : Bottom

2.1 : Top Perspective

2.2 : Bottom Perspective

2.3 : Front and rear view

2.4 : Right and left view

2.5 : Top

2.6 : Bottom

3.1 : Top Perspective

3.2 : Bottom Perspective

3.3 : Front and rear view

3.4 : Right and left view

3.5 : Top

3.6 : Bottom

This product incorporating the designs is a nail suitable to be attached to a sports shoe.

1 Claim, 18 Drawing Sheets
